Carlton V. Smith,

UNITED STATES PATENT OFFICE

CARLTON V. SMITH, OF COQUILLE, OREGON

DETONATING DEVICE

Application filed November 3, 1927. Serial No. 230,790.

The present invention relates to a detonating device, and aims to provide a novel and improved device of this character arranged in the form of a cane or at the end of a long 5 stick permitting it to be used in a safe manner by children for their amusement during celebrations and the like.

Another object of the invention is the provision of a detonating device constructed and 10 arranged so as to explode small caps arranged upon a film or strip of material, whereby they are automatically fed to firing position successively, or immediately after the exploding of a cap another will be rapidly advanced 15 to position to be exploded so as to permit the firing of the caps in rapid succession or in a manner to simulate the firing of an automatic gun or pistol.

It is also an object of the invention to provide a device of the above indicated character, which is simple and substantial in construction, which can be manufactured economically, and which will be thoroughly efficient and practical in use.

25 With the foregoing and other objects in view, which will be apparent as the description proceeds, the invention resides in the construction and arrangement of parts, as hereinafter described and claimed, it being understood that changes can be made within 30 the scope of what is claimed, without departing from the spirit of the invention.

The invention is illustrated in the accompanying drawings, wherein:

35 Figure 1 is a longitudinal section through my improved device.

Figure 2 is a side elevation showing the hinged casing swung downwardly.

Figure 3 is a longitudinal vertical section 40 taken on line 3-3 of Figure 1.

Figure 4 is a fragmentary enlarged elevation of the cap feeding mechanism.

Figure 5 is a fragmentary section taken 45 on line 5-5 of Figure 4, and

Figure 6 is a detail section taken on line 6-6 of Figure 1.

Referring to the drawings, it is to be noted 50 that the upper portion of the cane or stick 10 is broken away, and that the illustration is 55 confined to the cap supporting and firing

mechanism. The lower end of the cane handle 10 is slightly reduced, as at 11, and extends into an opening or socket 12 in the upper end of the cap supporting and firing body 13. By reducing the lower end of the cane handle 10, 55 a shoulder is provided which abuts against the upper end of the body so as to prevent movement of the body with relation to the cane handle when firing a cap. Any approved or well known method may be used 60 for securing the body 13 to the cane handle 10, such as by passing a pin through such members or threading the reduced portion 11 of the cane handle into the body 13.

The body 13 is provided with an enlarged 65 opening 14 which extends entirely through same from one side to the other, said opening being of rectangular shape and provided with a shoulder 15 at one side thereof forming the stationary firing surface. The rec- 70 tangular opening 14 extends downwardly to one side of the shoulder 15, as at 16, the purpose of which will be set forth as the description proceeds. Extending across the opening 14 adjacent its upper end is a small shaft 17 75

for supporting a coiled strip or film 18 having explosive caps 19 thereon. The shaft 17 has attached thereto a disk 20 for holding the coiled strip to one side of the opening 14. In order that the shaft 17 may be rotatably 80 mounted and be removed in order to mount other coiled strips thereon, a small opening 21 is provided in the body 13 at one side of the opening 14, while in the other side of 85 said opening there is a notch 22 in which is arranged a spring clip 23 for engaging the opposite end of the shaft 17 from that received in the opening 21. The spring clip 23 is secured in position in the notch 22 by means of a small screw 24, or the like, passed 90 through one end thereof, while the other end thereof is free to be yieldably forced so as to permit removal of the shaft 17. At the point on the spring clip where the end of the shaft 17 engages, said clip is curved so 95 as to form a slight pocket for receiving the end of the shaft 17. The notch 22 is of a width substantially the same as the diameter of the shaft 17 so as to prevent up and down movement of the shaft.

The strip 18 having the explosive caps 19 thereon extends downwardly and under a pair of spaced apart feeding disks 26 having teeth 28 which extend through perforations 29 at the opposite edges of the strip or film, said disks being spaced and fixed to a small collar 25. By providing the toothed disks 26 and small spacing collar it will be obvious that when the explosive caps pass under the collar they will not be damaged or ignited. The shoulder 15 on the body 13 has a pair of small grooves 30 therein in which the toothed disks 26 pass so as to assure engagement of the teeth with the strip 18. The disks and spacing collar to which they are fixed or integrally connected are mounted on a shaft 31 which extends across the opening 14 at the lower portion thereof and has its opposite end mounted in the body 13. At one side of the spaced disks and rigidly connected to one of said disks is a ratchet 32 which is engaged by a spring pressed pawl 33 so as to prevent retrograde movement of the disks, while rigidly carried by the disk 25 at the opposite side of the collar is one member of a clutch 34 which engages the other member 35 carried by a gear 36 which is also mounted on the shaft. A coil spring is arranged about the shaft 31 and interposed between the gear and the body 13 of the device for normally holding the gear in a position with the clutch member 35 thereon in engagement with the clutch member 34. It can be seen that when the gear 36 is turned in the proper direction, the clutch members 34 and 35 will cause the disks to be turned, but when the gear is turned in the opposite direction, the spring pressed pawl 33 will engage the ratchet 32 so as to prevent turning movement of the disks. When the disks are held against movement, the angled surfaces of the clutch teeth will cause the gear to be forced against tension of the spring 37 away from the reel so that said clutch teeth will not engage. By this arrangement, the strip 18 having the explosive caps 19 thereon will only be fed downwardly from the coiled portion of the strip 18.

Extending vertically through the openings 14 and 16, and through openings 38 and 39 in the body of the device is a sliding bar 40 having its upper end arranged in the opening 39 while its lower end projects below the body 13 of the device beyond the opening 38. On the lower end of the bar 40 is arranged a head 41 which is engaged by the lower end of a coil spring 42, said coil spring being in engagement with the lower end of the body 13 at its opposite end. The coil spring will normally hold the sliding bar 40 in its outermost position. On one side of the sliding bar 40 is arranged a toothed rack bar 40' the teeth 41' of which are in mesh with the teeth on the gear 36. The rack teeth are of greater width than the teeth on the gear 36 so as to cause continual engagement of the rack teeth and gear

teeth independent of the sliding position of the gear 36. From this it can be seen that when the bar 40 is slid in the body 13 the gear 36 will be rotated. Extending through the bar 40 is an elongated slot 43 which has pivotally arranged therein a trigger 44, said trigger being pivotally connected to the bar 40 by means of a pin 45. The lower end of the slot 43 only extends partially through the rod, as at 46, so as to provide a body to which the lower end of a leaf spring 47 is secured. The leaf spring 47 normally holds the trigger in position so that the upper end thereof projects slightly to one side of the sliding bar 40, the purpose of which will be set forth as so the description proceeds. The trigger 44 has a gradually curved cam surface 48 arranged below the point of pivot thereof which also normally extends to one side of the bar 40, and at the side opposite to that which the upper end of the trigger extends. The gradually curved cam surface 48 is in engagement with an angled surface 49 at one side of the opening 38, so that when the sliding bar 40 is forced upwardly against tension of the spring 42, the trigger will be swung on its pivot so that the upper end of the same moves into the bar 40 and is flush with the outer surface of said bar 40.

Also slidably arranged in the body 13 of the device is a hammer 50, which consists of a head 51 and shank 52, said shank being slidable in a correspondingly shaped opening 53 in said body above the opening 14. The lower end portion of the shank 52 as well as the hammer 50 are located within the opening 14 above the shoulder or anvil 15 and a coil spring 54 encircles the shank and is interposed between the head 51, and upper end wall of the opening 14. It will be readily seen that the coil spring normally holds the hammer in its downward position. The head of the hammer 51 is preferably of rectangular shape and is of sufficient size to prevent turning movement of the hammer in the opening through the body of the device as well as prevent it projecting beyond one side thereof, whereby to assure that the trigger 44 will engage under one end of the head 51 to raise the hammer against tension of the coil spring 54 when the sliding bar 40 is raised as by contact with the ground.

In order to form a protection for the stripped material having the caps 19 thereon, a casing 55 is provided having a pair of ears 56 on opposite sides and at the lower end thereof through which a bolt 57 extends, said bolt also extending through the lower end of the body 13 so as to provide a pivotal connection for the casing 55. Projecting from one side of the body is a lug 58 provided with a concaved upper surface which is adapted to be engaged by a spring lip arranged on the upper end of the casing 55 so as to hold the casing in proper position. When it is

desired to place a new strip in the device, the casing may be swung upon its pivot so as to gain access to the opening 14 in the body 13.

5 In operation, the casing 55 is swung downwardly to the position illustrated in Figure 2 of the drawings so as to permit the removal of the shaft 17. Said shaft may be easily removed by exerting an outward pull on the end thereof engaged by the spring clip 22. When the shaft 17 is removed a roll comprising the strip 18 with the explosive caps 19 thereon may be slid upon the shaft 17 and said shaft placed back in the body 13 so as to be rotatably supported by the body. The end of the strip 18 is then passed under the toothed disks 26 so that the teeth 28 will project through the perforations 29 in the strip. The casing may then be swung back to its position and the lug 58 will hold the same in closed position. The device is then ready for operation. By holding on the upper end of the cane handle or stick 10 and pressing the head 41 on the sliding bar 40 against a rigid object, as the ground, the bar 40 will be slid within the body 13 and cause the hammer 50 to also slide in an upward direction by engagement of the trigger therewith, the bar 40 being slid against tension of the coil spring 42, while the hammer is swung against tension of the coil spring 54. As the bar 40 moves upwardly, the trigger 44 which is in engagement with the head of the hammer is gradually moved from engagement with the head due to the angled surface 49 on the body 13 and the curved surface 48 on the trigger. As soon as the trigger automatically releases the hammer 50 it is returned to its initial position and strikes the explosive cap arranged therebeneath, said cap being exploded between the stationary shoulder or anvil 15 and the head 51 of the hammer. As the sliding bar 40 and the hammer are moved upwardly, the rack teeth 41 carried by the sliding bar 40 will rotate the gear 36 which will cause the feeding disks to also rotate and feed a new portion of the strip 18 having an explosive cap 19 thereon beneath the hammer. When pressure is relieved after the firing of the explosive cap, the coil spring 42 will return the sliding bar to initial position, and as the same is returned to its initial position, the spring urged pawl 33 will prevent retrograde movement of the disks due to its engagement with the ratchet 32, thereby preventing the old portion of the strip 18 from being fed backward. As the pawl 33 prevents retrograde movement of the disks, the gear 36 is forced to one side against tension of the spring 37 by reason of the inclined teeth of the clutch members 34 and 35 riding one on the other. The movement of the sliding bar 40 and the spacing of the explosive caps on the strip 18 are such that upon each operation of the device

explosive caps will be successively positioned under the hammer so as to be exploded automatically one after the other.

Having thus described my invention, what I claim as new is:

1. A detonating device comprising a body having an anvil, a spring urged bar slidably carried by said body, a spring urged hammer movably carried by said body, means on said bar for moving said hammer against tension of its spring on sliding movement of the bar, a coiled strip mounted in the body and having explosive caps thereon, means engaging said strip for feeding the same under the hammer, and means carried by the 70 slideable bar and operatively connected to said feeding means for feeding the strip upon sliding movement of said bar against tension of its spring, the means for moving said hammer being adapted to release said 75 hammer upon continued movement of the aforesaid bar so as to cause the hammer to explode a cap fed underneath the same. 80

2. A detonating device comprising a body, a spring urged bar slidably carried by said 90 body, a spring urged hammer movably carried by said body, a coiled strip carried by said body and having explosive caps thereon, means for feeding said strip under the hammer, a rack carried by said sliding bar, 95 a gear wheel operatively connected to said feeding means and meshing with said rack for feeding the strip upon movement of the sliding bar, and means on the sliding bar for engaging said hammer to move the same 100 against tension of the spring thereon and for releasing said hammer to explode a cap fed thereunder. 105

3. A detonating device comprising a body having an anvil on which caps are exploded, a spring urged hammer and operating bar movable in said body, a coiled strip mounted within the body and having explosive caps thereon, means for feeding the strip over the anvil by intermittent movement including a gearwheel, a rack carried by the operating bar and in mesh with said gearwheel, a clutch member carried by the strip feeding means, and an operating clutch member on the gearwheel adapted to feed the strip under the hammer upon sliding movement of the operating bar against tension of its spring; together with means on said operating bar for moving the hammer against the action of its spring, means for 110 releasing said hammer upon continued sliding movement of the operating bar, and means operatively connected to the strip feeding means for preventing retrograde movement thereof upon return movement of the spring actuated operating bar. 115

4. A detonating device comprising a casing having an anvil on which caps are exploded, a spring actuated operating bar slidably in said casing, a spring actuated 120

- hammer cooperating with the anvil and in parallel relation to the operating bar, means responsive to the operation of the bar for moving the hammer against the action of its spring, a coiled strip of explosive caps mounted in the casing, means for feeding the strip over the anvil on the operation of the aforesaid bar and including a gearwheel, and a rack on the operating bar in mesh with said gearwheel.
5. A detonating device comprising a casing having an anvil on which caps are exploded, a spring actuated operating bar slideable in said casing, a spring actuated hammer cooperating with the anvil and in parallel relation to the operating bar, means responsive to the operation of the bar for moving the hammer against the action of its spring, a coiled strip of explosive caps mounted in the casing, means for feeding the strip over the anvil on the operation of the aforesaid bar and including a gearwheel and clutch, and a rack on the operating bar in mesh with said gearwheel.
- 10 6. A detonating device comprising a casing having an anvil on which caps are exploded, a spring actuated bar slideable in the casing, a spring actuated hammer cooperating with the anvil and in parallel relation to the operating bar, and means responsive to the operation of the bar for moving the hammer against action of its spring; together with a coiled strip of explosive caps having perforations therein, toothed disks engaging the perforations for feeding the strip over the anvil, a clutch member in association with the toothed disks, a gearwheel carrying the companion clutch member, and a rack on the operating bar in mesh with the gearwheel.
- 15 7. A detonating device comprising a casing having an anvil on which caps are exploded and a spring actuated operating bar, a spring actuated hammer cooperating with the anvil and in parallel relation to the operating bar, and means responsive to the operation of the bar for moving the hammer against the action of its spring; together with a coiled strip of explosive caps mounted in the casing and having perforations therein, means for feeding the strip over the anvil, and means responsive to the operation of the operating bar for operating said feeding means.
- 20 8. A detonating device comprising a casing having an anvil on which caps are exploded and a spring actuated operating bar, a spring actuated hammer cooperating with the anvil and in parallel relation to the operating bar, and means responsive to the operation of the bar for moving the hammer against the action of its spring; together with a coiled strip of explosive caps mounted in the casing and having perforations therein, spaced apart toothed disks mounted

in the casing and engaging the strip to feed it over the anvil, a gearwheel and clutch connected to the disks, and a rack bar carried by the operating bar and in mesh with said gearwheel.

9. A detonating device comprising a casing having an anvil on which caps are exploded, a spring actuated operating bar slideable in the casing, a spring actuated hammer cooperating with the anvil and in parallel relation to the operating bar, and means responsive to the operation of the bar for moving the hammer against the action of its spring; together with a coiled strip of explosive caps mounted in the casing and having perforations therein, a shaft journaled in the casing, spaced apart disks on the shaft engaging the strip to feed it over the anvil, a pawl and ratchet on said shaft to prevent retrograde movement thereof, a gearwheel and clutch on said shaft for rotating the same, and a rack bar carried by the operating bar and in mesh with the gearwheel.
